UNITED STATES PATENT OFFICE.

FRANK THORNTON, JR., OF MANSFIELD, OHIO, ASSIGNOR TO WESTINGHOUSE ELECTRIC PRODUCTS COMPANY, A CORPORATION OF MICHIGAN.

AUTOMOBILE-ENGINE HEATER.

1,387,522.

Specification of Letters Patent. Patented Aug. 16, 1921.

Application filed December 10, 1919. Serial No. 343,896.

To all whom it may concern:

Be it known that I, FRANK THORNTON, Jr., a citizen of the United States, and a resident of Mansfield, in the county of Rich-
5 land and State of Ohio, have invented a new and useful Improvement in Automobile-Engine Heaters, of which the following is a specification.

My invention relates to electrical heating apparatus and particularly to small portable electric air heaters and it has for its object to provide apparatus of the character designated, which shall have new and novel means for holding the heater element in the casing.

15 My invention embodies a perforated cylindrical casing with suitable end caps, and a tubular heating element held in central axial alinement in the casing. The heating element comprises a refractory tube, on the 20 surface of which is wound a resistor wire, spacing blocks and a terminal block held in operative position by means of a bolt and nuts. The terminal block is clamped in one of the end caps by means of a screw-threaded 25 clamping ring and the bolt extends into and through the other end cap and is secured thereto by means of nuts.

In the single sheet of drawing, Figure 1 is a side view, with certain parts cut away, of 30 a device embodying my invention; Fig. 2 is a cross sectional view therethrough and Fig. 3 is a bottom end view thereof.

A cylindrical casing 1 is provided with a plurality of openings 2 which permit the 35 circulation of air through the casing. An end cap 3 is suitably secured to the casing at its upper end and an end cap 4 is secured to the lower end of the casing. A small circular opening 5 is provided in the center of 40 the end cap 3 for a purpose to be hereinafter set forth. A relatively large circular opening 6 is provided in the center of the end cap 4 and a screw-threaded tubular collar 7 is secured to the cap 4 concentric with the 45 opening 6.

A heating element 8 comprises a tubular member 9, on the outer surface of which is wound a suitable resistor 10, two spacing blocks 11, one at each end of the member 9, 50 a terminal block 12, a threaded rod 13 and a plurality of nuts 14. The tubular member 9, the blocks 11 and the terminal block 12 are held in their respective operative positions in axial alinement by means of the threaded 55 rod 13 and the nuts 14, as shown more spe-

cifically in Fig. 2. Terminal members 15, to which the ends of the resistor wire 10 are connected, are suitably secured to the outer end of the terminal block 12 and coöperate with a contact plug (not shown) to energize 60 the heater when desired. The terminal block 12 is provided with a tubular metal cover member 16, which is so formed as to have a larger diameter for that portion of its length which is in operative contact with 65 the block 12, and a somewhat smaller diameter for that portion which extends outwardly from the block 12 and covers the terminal bars 15. A shoulder is thus provided which may be clamped by a screw-threaded clamping collar 17 which is screwed on the collar 7, thus securing one end of the element 8 to the cap 4. The rod 13 extends beyond the upper one of the terminal blocks 11 and projects through the opening 75 5 and a nut 18, which is mounted thereon, operates to hold the upper end of the heater element securely in place in the cap 3.

A hook 19 is suitably secured to the casing 1, as by rivets 20, so that the heater may 80 be suspended from a suitable support or ledge if desired.

The heating element 8 may be removed by first unscrewing the clamping ring 17 from the collar 7 and the nut 18 from the rod 13, 85 after which the heating element may be drawn outwardly through the opening 6.

The device embodying my invention thus provides a light compact heating device, simple in construction and which may be put 90 to a variety of uses where a portable, light-weight electrical heater is required.

Various modifications may be made in the device without departing from the spirit and scope of my invention and I desire that 95 only such limitations shall be placed thereon as are imposed by the prior art or are specifically set forth in the appended claims.

I claim as my invention:

1. In an electrical heater, the combination 100 with a casing, of longitudinally-extending heating means in said casing, and supporting means for said heating means at each end of said casing and integral therewith.
2. In an electrical heater, the combination 105 with a casing, of heating means within said casing, and means integral with said casing at each end thereof for holding said heating means in a central longitudinal position in said casing.

3. In an electrical heater, the combination with a casing and end caps therefor, of a tubular heating element in said casing, and means for supporting said heating element 5 from the end caps of said casing.

4. In an electrical heater, the combination with a casing, of a tubular heating element, spacing blocks axially alined with said element, and means for holding said spacing 10 blocks and said heating element in operative relation to each other and in the said casing.

5. In an electrical heater, the combination with a casing, and end caps therefor, of a tubular heating element, a plurality of spacing blocks, a terminal block, and means for 15 maintaining said heating element, spacing blocks and terminal block in axial alinement with each other and in said casing.

6. In an electrical heater, the combination 20 with an elongated casing and end caps therefor, of a tubular heating element, a

plurality of spacing blocks, a terminal block, means for holding said heating element, spacing blocks and terminal block in axial alinement with each other, means for holding 25 said terminal block in one of said end caps, and means for holding said first-named means in the other of said end caps.

7. In an electric heater, the combination with a casing, end caps therefor, one of said caps having a central opening therein, and a screw-threaded collar secured to said cap and concentric with said opening, of a heater element, and a terminal block and a screw-threaded clamping ring coöperating with 30 35 said collar to clamp said terminal block in said end cap.

In testimony whereof, I have hereunto subscribed my name this 28th day of November, 1919.

FRANK THORNTON, Jr.
